Primary Examiner — Wendy L Arminio*Assistant Examiner* — Maheen Khurshid(74) *Attorney, Agent, or Firm* — Muncy, Geissler, Olds & Lowe, P.C.(57) **CLAIM**

The ornamental design for an eye testing apparatus, as shown and described.

DESCRIPTION

FIG. 1 is a top, front, and right side perspective view of an eye testing apparatus showing our new design;

FIG. 2 is a bottom, back, and left side perspective view thereof;

FIG. 3 is a front view thereof;

FIG. 4 is a back view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a cross sectional view cut along line 9-9 shown in FIG. 3.

In the drawings, the broken lines depict portions of the eye testing apparatus that form no part of the claimed design.

1 Claim, 9 Drawing Sheets(56)
